RAILWAY TRAFFIC CONTROLLING APPARATUS

Herbert A. Wallace, San Francisco, Calif., assignor to Westinghouse Air Brake Company, a corporation of Pennsylvania

Application December 22, 1949, Serial No. 134,374

4 Claims. (Cl. 246—428)

1

My invention relates to railway traffic controlling apparatus, and particularly to apparatus for controlling railway switches.

In the conventional type of railway switch, the switch points are rigidly connected and move together between two extreme positions, in each of which positions one switch point is closed against its adjacent rail, and the other switch point is open or spaced from its adjacent rail.

There is described in Letters Patent of the United States No. 2,375,890, issued to Harry L. Black on May 15, 1945, for Railway Traffic Controlling Apparatus, a railway switch in which both points are normally closed. The points are selectively opened for the passage of traffic over the switch by a switch operating mechanism including an operating rod having separate lost-motion connections with each of the switch points. The particular switch point opened in any instance is determined by the direction of movement of the switch operating rod from a normal central position.

An object of my invention is to provide an improved switch operating apparatus for a railway track switch of the type in which both switch points are normally closed.

Another object of my invention is to provide for a switch of the type described, improved operating apparatus including a switch machine for separately moving two operating rods which are individually connected to the switch points.

According to one form of my invention, the two operating rods for the two switch points are independently positioned by a pair of cam slots in a longitudinally movable motion plate.

In two other forms of my invention disclosed herein the switch machine includes a crankshaft which operates a pair of diametrically opposed crank pins. Each pin cooperates with a contoured cam slot in one of a pair of cam members which is attached to one of the two operating bars. Additional cooperating cam and follower mechanisms connect the cam members and the crankshaft and serve at times to lock one or both points.

In both forms of my invention, the switch points are held closed through their operating rods as long as the switch controlling member remains in its intermediate position. Where it is moved from this intermediate position to one of its extreme positions, one or the other of the two operating rods is moved thereby moving its associated switch point to its open position. The remaining switch point is locked in its closed position. Provision is made for locking both switch

2

points upon operation of the switch controlling member to either extreme position.

Other objects and characteristic features of my invention will become apparent as the description proceeds.

I shall describe two forms of railway switch operating apparatus embodying my invention, and shall then point out the novel features thereof in claims:

10. In the accompanying drawings; Fig. 1 is a top plan view, somewhat diagrammatic, showing a railway switch provided with one form of switch operating mechanism embodying my invention. Fig. 2 is a partial sectional view taken along the line II—II of Fig. 1, looking in the direction of the arrows. Fig. 3 is a view similar to Fig. 1, illustrating the use of a modified form of switch operating mechanism embodying my invention. Fig. 4 is a view similar to Fig. 2, taken along the line IV—IV of Fig. 3. Fig. 5 is an enlarged plan view of the essential parts of the switch operating mechanism of Fig. 3, with the cover and upper parts removed. Fig. 6 is a sectional view taken along the line VI—VI of Fig. 5. Fig. 7 is a view similar to Fig. 5 with still more parts removed to better illustrate certain of the structural details. Fig. 8 is a view similar to Fig. 5, with additional parts removed, illustrating another modified form of my invention.

Similar reference characters refer to similar parts in all the figures of the drawings.

Referring to Fig. 1, there is shown a railway track switch including fixed rails 1 and 2 and movable rails or switch points 3 and 4 associated with the rails 1 and 2, respectively. Switch point 3 is connected through an adjustable screw jaw 5 to a switch operating rod 6. Switch point 4 is similarly connected through an adjustable screw jaw 7 to a switch operating rod 8. The switch operating rods 6 and 8 are provided at their ends with pins 6a and 8a which are received in cam slots 9 and 10 formed in a motion plate 11 forming part of a switch and lock mechanism or switch machine generally indicated at 12.

In addition to the motion plate 11, the switch machine 12 includes suitable means for shifting the motion plate endwise. As shown in the drawing, this means is an electric motor 13. Any suitable manual or power operated means may be used for shifting the motion plate 11. Where an electric motor is used, it may be controlled by circuits similar to those described in Letters Patent of the United States No. 2,383,037, issued to Herbert L. Bone and Crawford E. Stap-

les on August 21, 1945, for Railway Traffic Controlling Apparatus.

A lock rod 14 is connected to the end of switch point 3 by means of an adjustable screw jaw 15. Another lock rod 16 is connected to the end of switch point 4 by means of an adjustable screw jaw 17. The ends of the lock rods 14 and 16 cooperate with a lock box 18 attached to the end of motion plate 11. The lock box 18 is provided with vertically offset and longitudinally spaced locking dogs 19 and 20 (Fig. 2). Locking dog 19 cooperates with notches 14a and 16a provided in the lower edges of the lock rods 14 and 16, while the locking dog 20 cooperates with other notches 14b and 16b provided in the upper edges of the lock rods 14 and 16. The screw jaws 15 and 17 are so adjusted that the notches 14b and 16b will both be aligned with the dog 20 when and only when the switch points 3 and 4 occupy the positions to permit traffic to move over the main track past the switch, and the notches 14a and 16a will both be aligned with the dog 19 when and only when the switch points occupy the proper positions to permit traffic to move into or out of the siding or branch track over the switch.

The motion plate 11 is normally in the intermediate position shown in the drawing, and is movable therefrom either to left or right extreme positions by the electric motor 13. Cam slot 9 is provided with a first longitudinal portion 9a, a diagonal portion 9b, and another longitudinal portion 9c. Cam slot 10 is similarly provided with a longitudinal portion 10a, a diagonal portion 10b, and another longitudinal portion 10c.

OPERATION OF FIGS. 1 AND 2

The parts are shown in the drawings in their normal positions. The motion plate 11 is in its intermediate position, and both switch points 3 and 4 are closed against their associated fixed rails 1 and 2. The locking dogs 19 and 20 are spaced from the lock rods 14 and 16, and neither the notches 14a and 16a nor the notches 14b and 16b are aligned.

With the parts in the positions shown, let it be assumed that the switch is operated to provide for a traffic movement along the main track. For this purpose, the motor 13 is energized to drive motion plate 11 to the right, as it appears in Fig. 1. As this movement takes place, pin 8a on switch operating rod 8 is engaged by the straight portion 10a of cam slot 10, so that operating rod 8 and switch point 4 are not moved. At the same time, pin 6a is engaged by diagonal portion 9b of cam slot 9. The pin 6a and operating rod 6 are thereby moved downwardly, opening switch point 3 away from its associated fixed rail 1. As the switch point 3 opens, the lock rod 14 is moved downwardly as it appears in Fig. 1, bringing notch 14b into alignment with notch 16b. When pin 6a reaches the end of diagonal portion 9b of the cam slot, the opening movement of the switch point 3 is completed, but the motion plate 11 has not moved far enough longitudinally to bring the locking dog 20 into the aligned notches 16b and 14b. Motion plate 11 continues to move to the right, however, and pin 6a is then held stationary by its engagement with longitudinal portion 9c of the slot 9. This additional movement of the motion plate 11 moves the locking dog 20 into the aligned notches 16b and 14b, thereby locking both switch points 3 and 4 in the proper posi-

tion for a traffic movement over the main line.

It may be readily seen that a corresponding movement of the motion plate 11 to the left from the intermediate position shown in the drawings will cause the switch point 3 to remain stationary while the switch point 4 is opened, and that after the switch point 4 is opened the locking dog 19 will move into engagement with the aligned notches 14a and 16a to lock the switch points in place.

FIGS. 3 TO 6

There is illustrated in Fig. 3 a track layout generally similar to that of Fig. 1, except that the switch machine 12 of Fig. 1 is replaced by a somewhat different type of switch machine generally indicated at 21. The switch machine 21 is generally similar to that illustrated in Letters Patent of the United States No. 1,293,290, issued to William Zabel on February 4, 1919, for Railway Traffic Controlling Apparatus. The switch machine 21 differs from that shown in the Zabel patent by the inclusion of a novel mechanism for driving two switch operating bars 22 and 23, which are pin connected to the switch operating rods 6 and 8. The lock box 18 of Fig. 1 is replaced in Fig. 3 by a similar lock box 24 having somewhat different dimensions. This lock box 24 is operated by a slide bar 25. Lock box 24 is provided with locking dogs 26 and 27 corresponding to the locking dogs 19 and 20 of Fig. 1.

The switch machine 21 includes a housing 28. A crankshaft 29 projects downwardly into the housing. Crankshaft 29 is illustrated as being driven by an electric motor 13, but may alternatively be driven by any suitable hand or power mechanism.

Within the casing 28, the crankshaft 29 carries a crank head 30 having a pair of diametrically opposite crank arms 31 and 32, which are provided at their ends with downwardly projecting pins 33 and 34, respectively, carrying rollers 35 and 36. The switch operating bar 22 extends across the housing 25 through suitable apertures therein, and therein carries a cam member generally indicated at 37. The cam member 37 is provided in its upper face with a cam slot or groove including portions 37a, 37b and 37c. The cam slot portion 37a is concentric with the crankshaft 29 when the parts are in the positions shown in Fig. 5. The straight diagonal cam slot portion 37b interconnects the slot portion 37a with the slot portion 37c. The cam slot portion 37c is offset to one side from the cam slot portion 37b and is concentric with the cam shaft 29 when the cam member is moved to its furthest left-hand position in the manner hereinafter set forth. The cam slot in the cam member 37 is adapted to receive the roller 36 and pin 34 carried on the end of crank arm 32. The cam member 37 is provided on its inner face with a cam surface 37d which is concentric with crankshaft 29 when the parts are in the positions illustrated in the drawings. It is preferred to construct the bar 22 and the cam member 37 as a one piece forging.

The switch operating bar 23 also extends through suitable apertures in the housing 25. Bar 23 carries a cam member 38 generally similar to the cam member 37. The cam member 38 is provided with cam slot portions 38a, 38b and 38c, which correspond to the cam slot portions 37a, 37b and 37c, respectively. The cam slot in cam member 38 is adapted to cooperate with the

rollers 35 and pin 33 carried on the end of crank arm 31. Cam member 38 is also provided with an inner cam surface 38d similar to the cam surface 37d. Bar 23 and cam member 38 are also preferably constructed as a one-piece forging.

At the right-hand side of Figs. 5, 6 and 7, bar 22 overlies bar 23. At the left-hand side, bar 23 overlies bar 22. This is accomplished by having the portion 22a of bar 22, which connects with the left side of cam member 37, downwardly offset from that portion of bar 22 which connects with the right side of cam member 37. Also, the portion 23a of bar 23, which connects with the right-hand side of cam member 38, is downwardly offset from the portion of bar 23 which connects with the left side of cam member 38. These downwardly offset portions 22a and 23a are also laterally offset near their connections with their respective cam members to provide necessary clearances.

Cam member 37 is cut away at 37e to permit passage therethrough of the bar 23, and cam member 38 is similarly cut away at 38e to permit passage therethrough of the bar 22.

The crank head 30 is provided with a second pair of arms 39 and 40 extending at right angles to and shorter than the arms 31 and 32. The arm 40 supports two downwardly projecting pins 41 and 42 having rollers 43 and 44, respectively. The rollers 43 and 44 cooperate under certain conditions to be later described, with the cam surface 38d on cam member 38 and with cam surface 37d on cam member 37, respectively.

The extremities of the arms 39 and 40 are contoured to be concentric with shaft 29, as indicated at 39a and 40a (Fig. 5). These contoured extremities cooperate with similarly contoured portions 25a of the slide bar 25 to prevent endwise movement of the slide bar when the parts are in the positions shown in the drawings.

The crank head 30 is provided with upwardly projecting pins 45 and 46.

The slide bar 25 extends completely through the casing 28, and is bifurcated at its center to straddle the crankshaft 29. The slide bar 25 is provided with downwardly projecting pins 47, 48 and 49, having rollers 50, 51 and 52, respectively, which at times cooperate with the pins 45 and 46 to produce endwise shifting movements of the slide bar 25, in a manner to be explained hereinafter.

The housing 28 comprises an upper casting 28a which may be fastened by any suitable means to a lower casting 28b. The interfitting faces of these castings are of irregular contour so that when the two castings are placed together, apertures 38c are formed to receive the operating bars 22 and 23 and apertures 28d are formed to receive the slide bar 25.

In assembling this mechanism, the operating bars 22 and 23 are first assembled and then placed in the lower casting 28b. The slide bar 25 is then assembled with the crankshaft 29 and crank head 30, and these parts are then assembled in the upper casting 28a. The two castings are then assembled, bringing all the parts into the operating relationships.

OPERATION OF FIGS 3 TO 6.

The parts are illustrated in Figs. 3 to 6, in their normal positions. Both the switch points 3 and 4 are closed, the crankshaft 29 is in its intermediate position, and neither set of notches

44a and 46a nor 14b and 16b of the lock rods is aligned.

Starting with the parts in this position, let it be assumed that it is desired to operate the switch to permit a traffic movement over the main track. For this purpose, the crankshaft 29 is rotated in a clockwise direction from the position shown in Fig. 5. As the crankshaft 29 rotates clockwise, the crank pin 34 moves through the straight portion 37b of the cam slot in the cam member 37, thereby moving the cam member 37 toward the crankshaft 29, and carrying the switch operating bar 22 in a direction to open the switch point 3.

During this clockwise movement of crankshaft 29, the pin 33 and roller 35 move upwardly through the concentric portion 38a of the cam slot in cam member 38. Cam member 38 and switch operating bar 23 are thereby held stationary. As this clockwise motion of crankshaft 29 continues, pin 33 and roller 35 move upwardly out of the open end of the slot portion 38a. Before the roller 35 is free of the cam slot portion 38a, however, the roller 43 on pin 41 engages cam surface 38d on the cam member 38 and is thereafter effective to prevent movement toward the right of cam member 38 and switch operating bar 23. As the clockwise motion of crankshaft 29 continues further, roller 44 on pin 42 also engages cam surface 38d to aid roller 43 on pin 41 in holding the cam member 38 stationary.

When the crankshaft has been rotated approximately 70 degrees, the pin 34 and the roller 36 will have moved the cam member 37 to its extreme left-hand position so that the cam slot portion 37c of the cam member is in line with the crankshaft 29 as indicated by the dashed line position in Fig. 5. With the cam member 37 in this position, the cam slot portion 37a is concentric with the crankshaft. The roller 36 at this point will be leaving the cam slot portion 37b and entering the cam slot portion 37c. Further rotation of the crankshaft will move the roller 36 through the now concentric slot portion 37c without further movement of the cam member 37.

The tendency of the cam member 37 to move to the right due to the self bias of the switch point 3 toward its closed position is prevented by the tangential engagement of the roller 36 and the inner edge of the cam slot 37c. A tangent drawn at the point of engagement of the roller 36 with the inner edge of the cam slot portion 37c will have a slope, while the force exerted by the bias of the switch point 3 on the cam member 37 will be in a horizontal direction. Camming action will thus be provided between the roller 36 and the cam slot portion 37c to hold the cam member 37 stationary against the bias action of the switch point 3 while the roller 36 is moved from the 70 degree position to the 90 degree position by the crankshaft. When the roller has been moved to its 90 degree position, the slope of the tangent drawn at the point of contact of the roller and the cam slot portion 37c will coincide with the horizontal force exerted by the switch point. At this point, however, the roller 36 will be in the end of the slot portion 37c to prevent the cam member 37 from snapping back. The switch point 3 is thus fully opened when the crankshaft is moved 70 degrees and held open during the last 20 degrees of movement of the crankshaft.

When the crankshaft has rotated approximately 70 degrees, pin 45 engages roller 51 and starts to move slide bar 25 endwise. Notch 46b in lock

rod 16 is aligned with lock dog 27, so that this initial movement of slide bar 25 starts the dog 27 moving through notch 16b. The switch point 3 being open, notch 14b on lock rod 14 is aligned with notch 16b and the lock dog 27. As the crank shaft 29 continues to move to the 90 degree position, the pin 45 moves the roller 51 and the slide bar 25 sufficiently to bring the locking dog 27 into the notches 16b and 14b, thereby locking both the switch points in the proper position for a 10 traffic movement over the main line.

It is believed that the operation of the mechanism during a reversal of the movement just described will be apparent without further description except to state that in the counter-clockwise movement of the pin 45, the roller 50 will be engaged to return the slide bar 25 to its normal position as shown in the drawings. It is likewise believed that the operation of the mechanism in the opposite sense to permit a traffic movement over the side track is also obvious. It may be briefly pointed out that such an operation is accomplished by rotating the crankshaft 29 in a counterclockwise direction from the position shown in the drawing, thereby operating cam member 38 and switch operating bar 23 in the same manner that cam member 37 and switch operating bar 22 were moved in the operation described above.

FIG. 8

This figure illustrates a modified form of crank head and cam mechanism for connecting the crankshaft 29 of Figs. 3 to 6 to the switch operating bars. In this figure, only the switch operating bars, the crank head and their interconnecting cam mechanism are shown, the remaining parts being omitted for the sake of simplicity. The omitted parts may be the same as or similar to those shown in Figs. 3-6.

Referring to Fig. 8 in detail, there may be seen two switch operating bars 53 and 54, corresponding respectively to the operating bars 22 and 23 of Figs. 3-6. The operating bars 53 and 54 have central offset portions 53a and 54a corresponding respectively to the offset portions 22a and 23a of Figs. 3-6. The operating bars 53 and 54 carry integrally forged cam members 55 and 56, corresponding generally to, but specifically different from, the cam members 37 and 38 of Figs. 3-6.

Cam member 55 has a cam slot including an arcuate portion 55a, which in the position shown is concentric with the crankshaft 29, and a straight diagonal portion 55b, which connects with the lower end of cam slot portion 55a. Cam member 56 has corresponding cam slot portions 56a and 56b.

Cam member 55 has an outer peripheral cam surface 55c, which is contiguous with another peripheral cam surface 55d. The cam member 55 also has an inner peripheral cam surface 55e, which in the position shown, is concentric with crankshaft 29. Cam member 56 has corresponding surfaces 56c, 56d and 56e.

Crankshaft 29 carries a crank head 57, corresponding generally to, but specifically different from, the crank head 40 of Figs. 3 to 6. Crank head 57 is provided with oppositely extending arms 58 and 59, which respectively carry at their extremities downwardly depending pins 60 and 61 carrying rollers 62 and 63. Pin 60 and its roller 62 move in the cam slot portions 55a and 55b of cam member 55, while pin 61 and its roller 63 move in the cam slot portions 56a and 56b of cam member 56.

Crank head 57 also has an arm 64, extending downwardly as it appears in Fig. 8, which carries a downwardly depending cam lug 65 having a surface 65a concentric with shaft 29 and at times cooperating with the cam surfaces 55e and 56e on the cam members 55 and 56.

Crank head 57 is also provided with an arm 66, extending upwardly as it appears in Fig. 8, which carries a downwardly depending pin 67 carrying a roller 68. Roller 68 at times cooperates with cam surfaces 55c, 55d, 56c and 56d, as described below.

OPERATION—FIG. 8

The parts are shown in their normal positions, in which both switch points are closed. Let it be assumed that the crankshaft 29 is now operated clockwise to open one of the switch points.

As the crankshaft 29 moves clockwise, pin 61 and roller 63 move upwardly through concentric slot 56a, so that operating bar 54 is not moved. Before roller 63 moves out of the open end of slot 56a, cam lug 65 moves into alignment with cam surface 56e to hold the operating bar 54 against movement to the right (in a switch point opening direction). The switch point operated by bar 54 therefore remains closed during clockwise movement of crankshaft 29.

As the crankshaft 29 moves clockwise, pin 60 and roller 62 move down the diagonal cam slot 55b, driving the cam member 55 and operating bar 53 to the left, in a switch point opening direction. Before roller 62 reaches the lower left edge of the slot 55b, roller 68 engages the cam surface 55c, so that leftward movement of bar 53 is continued. This movement of bar 53 continues until crankshaft 29 has rotated approximately 70 degrees, at which position roller 68 reaches the end of cam surface 55c and engages cam surface 55d. The latter cam surface is at this time concentric with crankshaft 29, so that further rotation of the crankshaft does not move the switch operating bar 53 or its associated switch point. Cam surface 55d is long enough to permit an additional 20 degrees of rotation of the crankshaft 29 without moving the switch point. This additional movement is utilized to operate the switch point locking mechanism which may include a slide bar such as that shown at 25 in Figs. 3-6, and its associated mechanism.

It is believed that from the foregoing description, the analogous operation of the mechanism during restoration of the parts to their normal positions can be readily understood without a detailed description. It is believed that the operation of the other switch point, by rotation of the crankshaft 29 counterclockwise from its normal position, can also be readily understood.

It will be readily apparent to those skilled in the art that the various switch operating mechanisms shown and described may be mounted on either side of a switch. In the case of the mechanisms shown in Figs. 3-7, and 8, the switch operating bars project from the housing in both directions, and either end of a bar may be utilized to operate a switch point. It should be readily apparent that the motion plate mechanism 12 of Fig. 1 is also readily adaptable to mounting on either side of a switch operated thereby.

Although I have herein shown and described only three forms of railway switch operating apparatus embodying my invention, it is understood that various changes and modifications may be made therein within the scope of the appended

claims without departing from the spirit and scope of my invention.

Having thus described by invention, what I claim is:

1. Apparatus for operating a railway switch having independently movable switch points, comprising a pair of operating rods, each connected to one of said points, and a switch machine for separately operating said rods including a crankshaft rotatable between an intermediate position and opposite extreme positions, a pair of crank arms fixed on the shaft for rotation therewith, a pair of diametrically opposite crank pins on said arms, a pair of cam members, one attached to each of said rods, said cam members being located on opposite sides of said shaft and each having a cam slot to receive one of said crank pins, said cam slots being arranged so that when said shaft is in its intermediate position said rods are held with their switch points closed, said slots having first portions respectively contoured to cause movement of one or the other cam member toward the shaft and consequent opening of one or the other switch point as the shaft rotates in opposite directions from its intermediate position, said slots having second portions concentric with the shaft to hold each cam member fixed as the other cam member moves toward the shaft, said second slot portions being effective only during initial movement of the cam shaft from its intermediate position, a second pair of crank pins on said arms, and concentric cam surfaces on said cam members for engagement by said second crank pins when said second slot portions become ineffective to hold said cam members fixed during continued rotation of the cam shaft following said initial movement.

2. Apparatus for operating a railway switch having independently movable switch points, comprising a pair of operating rods, each connected to one of said points, a pair of lock bars, each connected to one of said points, a switch and lock movement including a member rotatable between an intermediate position and opposite extreme positions, camming means on said rotatable member, a pair of cam members, each connecting said member to one of said rods, each said cam members having a first portion contoured so that upon rotation of the rotatable member between its intermediate position and one extreme position the associated rod remains stationary with its switch point closed, a second portion contoured so that upon rotation of the rotatable member from its intermediate position toward its other extreme position the associated rod is operated in a direction to open its associated switch point, a cam surface concentric with said rotatable member and cooperating with the camming means thereon to hold the first mentioned rod against movement during rotation of said member to the one extreme position and to hold the second mentioned rod against movement during rotation of said member to its other extreme position; and means in said switch and lock movement operated by said member as it completes its movement to either extreme position and cooperating with said lock bars to lock both switch points against movement when said member is in either extreme position.

3. Apparatus for operating a railway switch having independently movable switch points, comprising a pair of operating rods, each connected to one of said points, a pair of lock bars, each connected to one of said points, and a switch and lock movement including a crankshaft ro-

tatable between an intermediate position and opposite extreme positions, a pair of diametrically opposite crank pins rotated by said shaft, a pair of cam members, one attached to each of said rods, each said cam member having a cam slot to receive one of said pins, each said slot having a first portion concentric with said shaft and effective when said shaft is rotated in one direction from its intermediate position to hold its associated rod stationary with its switch point closed, and a second portion contoured so that when the shaft is rotated in the opposite direction from its intermediate position its associated rod is operated in a direction to open its switch point, a second pair of diametrically opposite crank pins rotated by said shaft, a slide bar movable by said second set of pins when said crankshaft completes its rotation to either extreme position, and a lock box movable by said slide bar and cooperating with said locking bars to lock both switch points against movement when said crankshaft is in either extreme position.

4. Apparatus for operating a railway switch having independently movable switch points, comprising a pair of operating rods, each connected to one of said points; a pair of lock bars each connected to one of said points, and a switch and lock movement including a crankshaft rotatable between an intermediate position and opposite extreme positions, a pair of crank arms fixed on the shaft for rotation therewith, a pair of diametrically opposite crank pins on said arms, a pair of cam members, one attached to each of said rods, said cam members being located on opposite sides of said shaft and each having a cam slot to receive one of said crank pins, said cam slots being arranged so that when said shaft is in its intermediate position said rods are held with their switch points closed, said slots having first portions respectively contoured to cause movement of one or the other cam member toward the shaft and consequent opening of one or the other switch point as the shaft rotates in opposite directions from its intermediate position, said slots having second portions concentric with the shaft to hold each cam member fixed as the other cam member moves toward the shaft, said second slot portions being effective only during initial movement of the cam shaft from its intermediate position, a second pair of crank pins on said arms, and concentric cam surfaces on said cam members for engagement by said second crank pins when said second slot portions become ineffective to hold said cam members fixed during continued rotation of the cam shaft following said initial movement, a third pair of diametrically opposite crank pins rotatable with said crankshaft, a slide bar movable by said third pair of pins when said crankshaft completes its rotation to either extreme position, and a lock box movable by said slide bar and cooperating with said locking bars to lock both switch points against movement when said crankshaft is in either extreme position.

HERBERT A. WALLACE.
